Primary Examiner — Elizabeth Albert(74) *Attorney, Agent, or Firm* — Knobbe Martens Olson & Bear LLP(57) **CLAIM**

Ornamental design for a switch, as shown and described.

DESCRIPTION

FIG. 1.1 is a front perspective view of the switch showing my new design.

FIG. 1.2 is a front elevational view thereof.

FIG. 1.3 is a right side elevation view thereof. A left side elevational view is a mirror image thereof.

FIG. 1.4 is a top plan view thereof. A bottom plan view is a mirror image thereof.

The broken lines in FIGS. 1.2-1.4 represent environmental features that form no part of the claimed design.

1 Claim, 4 Drawing Sheets(56)
